CLOSURE CAP FOR COLLAPSIBLE CONTAINERS

Santiago M. Alberdi, Jr., Montes de Oca, Argentina

Application May 25, 1951, Serial No. 228,220

5 Claims. (Cl. 222—494)

The present invention relates to closure caps for collapsible containers and more particularly to closure caps for containers utilized for containing extrudable pasty materials such for example as tooth paste, ointments, beauty creams and sandwich spreads.

Heretofore such containers which comprise an extrusion nozzle, have been provided with a screw-on closure cap having an imperforate top whereby said cap has had to be removed every time it was desired to squeeze some of the contents out of the container. Besides being troublesome, this circumstance frequently led to the losing of the closure cap so that in many cases the container with its contents had to be discarded, or at best there existed the danger of an undesired extrusion taking place by inadvertent compression of the unclosed container.

The principal object, therefore, of the present invention is to provide a closure cap for collapsible containers of the kind described which cap may be kept permanently on the container nozzle and yet permit immediate extrusion of the contents.

Another object is to provide a removable closure cap for collapsible containers, comprising a diaphragm type valve arrangement of a novel construction.

These and other objects and advantages of the present invention will become more readily apparent in the course of the following detailed description of certain preferred embodiments thereof illustrated by way of example in the accompanying drawings.

In the drawings:

Fig. 1 is a top plan view of a closure cap according to the present invention.

Fig. 2 is a section along the line II—II of Fig. 1.

Fig. 3 is a plan view showing a diaphragm type valve as used in the present invention.

Fig. 4 is a diametral section of a modified form of my novel closure cap.

Fig. 5 is a perspective view of a sealing spider for use in embodiments of the type shown in Fig. 4.

Fig. 6 is a perspective view of a collapsible container head fitted with my novel closure cap during use, and

Fig. 7 is a similar view showing the cap after use.

Referring first to Figs. 1 through 3, I have there illustrated a valved closure cap according to the present invention comprising a hollow body 6 including a skirt portion 7 which is shown as internally screw threaded at 8 to enable the closure cap to be screwed on to the nozzles of conventional collapsible containers. Said skirt portion is open at one end to receive such nozzle and at the other end has an inwardly directed flange 9 defining a relatively large circular mouth 10 which is normally substantially closed by a diaphragm 11.

As best seen in Fig. 3 said diaphragm consists of a circular piece of thin resilient sheet material centrally pierced to provide an orifice 12 of very small diameter, say of the order of 1.0 or 0.5 mm. or less. The material of the diaphragm is also cut to define a plurality of slits, preferably three slits 13 radiating from the orifice 12 in mutually equiangular relationship and extending to points spaced

2

inwardly of the edge 14 of diaphragm thereby defining an annular imperforate marginal portion 15 and three centrally directed generally triangular tongues or flaps 16. Said marginal portion is adapted to be secured to said flange

5 9. It may be secured thereto by means of an adhesive cement or by other means such as a spring ring, but preferably the diaphragm has said margin 15 embedded in the material of said flange 9, as shown in Fig. 2. This method of assembly is particularly suitable when the body 6 of 10 the closure cap is made of molded material as then the diaphragm can be treated as an insert.

While various materials such as stiff sheet rubber and plastic base sheet materials having a sufficient degree of elasticity, may be used, I have found that very satisfactory results as to both the operation and the durability of the diaphragm can be obtained by using the cellulosic backing material now employed for photographic and, more particularly, radiographic films. Such backing material has a convenient thickness, is sufficiently springy and is readily worked. It is however to be understood that I do not intend to restrict the invention to the use of any particular material since any material which on being given the form shown in Fig. 3, has sufficient flexibility and springiness to give the tongues 16 adequate opening and restoring powers, may be used for practicing this invention. The material selected should also, of course, meet any of the requirements of a circumstantial nature, such as being non-toxic and innocuous to the contents of the container to which the closure cap is to be applied.

20 30 It is of course desirable that the tongues should not be so stiff as to require an abnormal effort on the part of the user, to extrude the contents of the collapsible container, yet the tongues should have sufficient restoring powers to regain substantially their coplanar relationship when the extruding pressure on the contents of the container has ceased.

In order to assist the opening and closing action of the tongues 16, the slits 13 are preferably of some positive though very small width, as for example, they may be a fraction of a millimeter wide.

40 Hence in the embodiment hereinabove described, on the application of extruding pressure to the container 17 (Figs. 6 and 7) a three armed column of pasty content 18 having arms or webs 19 radiating from a central core 20 will issue from the diaphragm 11, the tongues 16 of which will be deflected outwardly as shown in Fig. 6 whereby the sides of the arms or webs 19 will not be plane but somewhat thickened as will also the central portion or core 20 of column 18.

50 55 When a sufficient length of pasty contents has been extruded and deposited on a receiving surface (not shown) such as a tooth-brush, the pressure is relieved and the column may be broken off by the usual wiping movement given to the container and hence to the outlet thereof, which in the present invention is the closure cap 6.

The resiliency of the material of the diaphragm should be sufficient to cause the flaps 16 to tend strongly to return to their coplanar positions, their return to such position or to a close approximation thereto, being materially assisted by the wiping action mentioned hereinabove. Thus, after the container has been used it may just be laid aside and the diaphragm 11 will be sufficient to retain the contents in the container and to protect all but a very small area indeed from the influence of the atmosphere.

60 65 70 When it is desired that the area of the pasty material exposed after use, that is to say the area represented by the material in the central orifice 12 and the slits 13, shall be reduced to a minimum, a sealing spider 21 (see Figs. 4 and 5) may be provided closely behind the diaphragm 11. Said spider comprises a central boss 22 of a size to block up the orifice 12, and three radial legs 23 each positioned

in alignment with one of the slits 13 and of a size to block said slits throughout their length. Said spider is mounted inside the hollow body 6 behind the diaphragm 11 and closely adjacent thereto, as indicated in Fig. 4. The central boss 22 may be long enough to project through the orifice 12 and the legs 23 may be round with their ends imbedded in the material of the body 6. In the modification shown in Fig. 5 the legs 23a are oval or streamline in contour and are therefore adapted to extend at least partly into the slits of a diaphragm. The boss 22a is also of a streamline contour and would also project through said orifice. By the use of the spider, substantially complete closure of the dispensing end of the closure cap can be ensured by properly choosing the elasticity of the diaphragm, having regard to the viscosity of the plastic material.

When the contents of a particular container to which the closure cap has been applied, are exhausted, said cap may be removed, washed or otherwise cleaned and applied to another container. When so applied, the tongues 16 will be coplanar and, particularly if the sealing spider is provided, will constitute a satisfactory closure so that a new, full container can be marketed directly when fitted with only a closure cap according to the present invention. If desired, of course, a wafer of sheet material may be affixed to the dispensing end of the cap. For instance the wafer may be stuck to the flange 9.

Although I have described the present invention with particular reference to certain preferred embodiments, it is to be understood that I do not desire to be limited thereby but that I may make such changes and modifications therein as lie within the scope of the appended claims.

I claim:

1. A closure cap for collapsible containers including an externally screw threaded nozzle, said closure cap comprising a hollow body including a skirt portion internally threaded for screwing onto said nozzle and being open at one end, the other end of said hollow body defining a relatively large mouth, a diaphragm of resilient sheet material located inside said hollow body and extending over said mouth, said diaphragm being perforated to define a central relatively small orifice and a plurality of slits radiating from said orifice in mutually substantially equi-angular relationship and extending to points spaced inwardly of the perimeter of said diaphragm to define an annular imperforate marginal portion and a plurality of substantially triangular outwardly deflectable tongues having apices directed towards said orifice, and fixing means securing said marginal portion in position in said hollow body, a sealing spider for said orifice and plurality of slits, said sealing spider being located inside said hollow body adjacent said diaphragm and having a central boss and a plurality of legs, said central boss being in alignment and extending into said orifice and said plurality of legs extending into said plurality of slits.

2. A closure cap for collapsible containers including a nozzle, said closure cap comprising a hollow body including a skirt portion of a size to fit over said nozzle, and open at one end, the other end of said hollow body defining a relatively large mouth, a diaphragm of resilient sheet material located inside said hollow body and extending over said mouth, said diaphragm being perforated to define a central relatively small orifice and a plurality of slits radiating from said orifice in mutually substantially equi-angular relationship and extending to points spaced inwardly of the perimeter of said diaphragm to define an annular imperforate marginal portion and a plurality of substantially triangular outwardly deflectable tongues having apices directed towards said orifice, said marginal portion being embedded in the material of said skirt portion, a sealing spider for said orifice and plurality of slits, said sealing spider being located inside said hollow body adjacent said diaphragm and having a central boss and a

plurality of legs, said central boss being in alignment and extending into said orifice and said plurality of legs extending into said plurality of slits, said legs having free ends embedded in said skirt portion.

3. A closure cap for collapsible containers including a nozzle, said closure cap comprising a hollow body including a skirt portion of a size to fit over said nozzle and being open at one end, the other end of said skirt portion defining a relatively large mouth, a diaphragm of resilient sheet material located inside said hollow body and extending over said mouth, said diaphragm being perforated to define a central relatively narrow orifice and a plurality of relatively narrow slits radiating from said orifice and extending each to a point spaced inwardly of the perimeter of said diaphragm to define an imperforate marginal portion and a plurality of outwardly deflectable triangular tongues having apices directed towards said orifice, a sealing spider permanently located inside said hollow body adjacent said diaphragm and on the side thereof remote from said mouth, said spider comprising a central boss located in alignment with said orifice and a plurality of radial legs aligned with said slits.

4. A closure cap for collapsible containers including a nozzle, said closure cap comprising a hollow body including a skirt portion of a size to fit over said nozzle and being open at one end, the other end of skirt portion defining a relatively large mouth, a diaphragm of resilient sheet material located inside said hollow body and extending over said mouth, said diaphragm being perforated to define a central relatively narrow orifice and a plurality of relatively narrow slits radiating from said orifice and extending each to a point spaced inwardly of the perimeter of said diaphragm to define an imperforate marginal portion and a plurality of triangular tongues having apices directed towards said orifice, said marginal portion being embedded in the material of said hollow body, a sealing spider permanently located inside said hollow body adjacent said diaphragm and on the side thereof remote from said mouth, said spider comprising a central streamline boss located in alignment with said orifice and extending thereto, and a plurality of radial streamline legs aligned with said slits having free ends embedded in the material of said hollow body and extending into said slits.

5. A closure cap for collapsible containers comprising a hollow body including a skirt portion open at one end, the other end of said hollow body defining a relatively large mouth, a diaphragm of resilient sheet material located inside said hollow body and extending over said mouth, said diaphragm being perforated to define a central relatively small orifice and a plurality of slits radiating from said orifice in mutually substantially equi-angular relationship and extending to points spaced inwardly of the perimeter of said diaphragm to define an annular imperforate marginal portion and a plurality of substantially triangular outwardly deflectable tongues having apices directed towards said orifice, and fixing means securing said marginal portion in position in said hollow body, a sealing spider for said orifice and plurality of slits, said sealing spider being located inside said hollow body adjacent said diaphragm and having a central boss and a plurality of legs, said central boss being in alignment and extending into said orifice and said plurality of legs extending into said plurality of slits.
